(57) **CLAIM**

The ornamental design for a utility pole, as shown and described.

DESCRIPTION

FIG. 1 is a side view of a first side of the utility pole;

FIG. 2 is a side view of a second side thereof;

FIG. 3 is a top view thereof;

FIG. 4 is a bottom view thereof; and,

FIG. 5 is a side view of the fourth side thereof.

A view of the third side of the utility pole is not provided because it is identical to the first side thereof.

The broken lines in FIGS. 1 and 2 are for the purpose of illustrating environment and form no part of the claimed design.
